Primary Examiner — Brett Miller(74) *Attorney, Agent, or Firm* — Carr & Ferrell LLP(57) **CLAIM**

The ornamental design for a geodesic dome, as shown and described.

DESCRIPTION

FIG. 1 is a perspective view of a geodesic dome showing our new design.

FIG. 2 is a right view thereof.

FIG. 3 is a left view thereof.

FIG. 4 is a front view thereof.

FIG. 5 is a back view thereof.

FIG. 6 is a top view thereof; and,

FIG. 7 is a bottom view thereof.

The broken lines are directed to environment. None of the broken lines form a part of the claimed design.

1 Claim, 5 Drawing Sheets(56)
